INLET FUNNEL FOR GRAIN DRYING BINS

Vernon H. Sietmann, Laurel, Iowa

Filed Apr. 21, 1971, Ser. No. 136,304

Term of patent 14 years

Int. Cl. D15—99

U.S. CL. D55—1 H

FIG. 1 is a top perspective view of an inlet funnel for grain drying bins;

FIG. 2 is a top plan view of the unit shown in FIG. 1;

FIG. 3 is a side elevation thereof as viewed from the bottom of FIG. 2;

FIG. 4 is a bottom plan view thereof; and

FIG. 5 is a side elevational view of an inlet funnel for grain drying bins showing my new design wherein the lower canopy has been removed to expose the configuration of the lower ends of the centrally located baffle elements. The top and bottom plan views thereof are essentially identical to the top and bottom plan views depicted in FIGS. 2 and 4, respectively.

The characteristic features of my new design and the common features of the two illustrated embodiments of my new design consist primarily in the configurations of the centrally located baffle elements.

I claim:

The ornamental design for an inlet funnel for grain drying bins, substantially as described and shown.
